[57] CLAIM

The ornamental design for a wheel for manually operating an animal food dispensing machine, as shown and described.

DESCRIPTION

FIG. 1 is a front perspective view of a wheel for manually operating an animal food dispensing machine showing our new design, the food dispensing machine being shown in broken lines for illustrative purposes only;

FIG. 2 is an enlarged top plan view thereof;

FIG. 3 is an enlarged left side elevational view thereof;

FIG. 4 is an enlarged front elevational view thereof;

FIG. 5 is an enlarged right side elevational view thereof;

FIG. 6 is an enlarged bottom plan view thereof;

FIG. 7 is an enlarged rear elevational view thereof;

FIG. 8 is a perspective view of the second embodiment of the design of FIG. 1, the animal food dispensing machine being shown in broken lines for illustrative purposes only;

FIG. 9 is an enlarged top plan view of FIG. 8;

FIG. 10 is an enlarged left side elevational view of FIG. 8;

FIG. 11 is an enlarged front elevational view of FIG. 8;

FIG. 12 is an enlarged right side elevational view of FIG. 8;

FIG. 13 is an enlarged bottom plan view of FIG. 8;

FIG. 14 is an enlarged rear elevational view of FIG. 8.
